(57) **CLAIM**

The ornamental design for a set of components for a magnetic button, as shown and described.

DESCRIPTION

FIG. 1 is a perspective front view of a set of components for a magnetic button, showing my new design;

FIG. 2 is a perspective rear view thereof;

FIG. 3 is a front view thereof;

FIG. 4 is a rear view thereof;

FIG. 5 is a left side view thereof with a right side view being a mirror image; and,

FIG. 6 is a top view thereof with a bottom view being a mirror image.
